GUN SIGHT MOUNTING

Maynard W. Tucker, Ypsilanti, Mich., assignor to
 Higgins-Tucker Motor Co., Inc., Ypsilanti,
 Mich., a corporation of Louisiana

Application March 30, 1943, Serial No. 481,121

3 Claims. (Cl. 33—48)

The present invention relates to gun sights and more specifically to sighting means for machine guns or the like.

In the mounting of machine guns in the turrets of planes, tanks and other war machines, means is usually provided to enable the guns to be aimed in any direction through a considerable horizontal angle—often a complete circle—and the sighting of the gun or group of guns in such movement offers no great problem.

However, in such mountings of the guns there must also be provided means by which the guns may be elevated or depressed and such means often is required to permit the gun to assume a vertical position. And, when such a gun is moved so as to change its elevation, a change in its trajectory must be compensated for in order to have satisfactory marksmanship.

The present invention, therefore, has as one of its main objects, a gun sight which, not only provides accurate aiming while the gun remains horizontal, but compensates for trajectory changes when the muzzle, or muzzles of a group of guns, is elevated or depressed.

Furthermore, at all angles of elevation and depression, the gunner may assume a most natural and comfortable position since the relative position between him and the sight is practically constant.

Another object is a gunsight mounting of the type indicated which shall be simple in construction and adjustment; accurate in operation; and one not likely to get out of order.

Other objects and advantages will be apparent to those skilled in the art upon reference to the following description and the accompanying drawings in which

Figure 1 is a side elevation of a gunsight and gun mount embodying the present invention.

Figure 2 is a perspective view on a somewhat larger scale.

Figure 3 is a front elevation of the same.

Figure 4 is a plan view of the sight and mount assembly.

Figure 5 is a section on line 5—5 of Figure 4.

Figure 6 is a section on line 6—6 of Figure 1.

Figure 7 is a section on line 7—7 of Figure 1.

Figure 8 is a vertical section of the rotatable hub as if on line 8—8 of Figure 1.

Figures 9, 10 and 11 are diagrammatic side elevations showing the sight and mount in as many positions.

Figure 12 is a sectional view showing a modification of the structure shown in Figure 5.

Figure 13 is a perspective view on somewhat larger scale.

Figure 14 is a side elevation of a modified gun-sight and gun mount embodying the present invention.

Figure 15 is a front elevation of the same.

Figure 16 is a section on line 16—16 of Figure 15.

In the drawings, there is shown at 20 the lower stationary portion of a turret which may be mounted upon or be a part of any suitable vehicle or fixed fortification. Within this is mounted a suitable rotatable pedestal (not shown) carrying the mechanism for producing the horizontal and vertical traverse of the machine guns mentioned later on in the description.

Carried by the pedestal mentioned is a frame member or support 21 provided with a forwardly extending portion secured to a ring 22 rotatably mounted upon the upper edge of turret 20 upon suitable ball bearings 23. This ring insures smooth operation during horizontal traverse and also helps sustain the shock of recoil when the machine guns are being fired.

23 The frame member 21 supports at its upper end a ring or drum 25 in the ends of which are rotatably mounted a pair of discs 26, suitable ball bearings 27 being used to provide for free movement. These discs 26 are fixed together by means

30 of the spacing bars 28 of which there are several. Also carried by frame member 21 and extending diagonally upward and toward the rear over the drum 25, is an arm 30 serving as a stationary part of the sighting mechanism.

35 The discs 26 have fixed to them the gun mounting platforms 31, upon which a pair of machine guns 32 may be mounted, and also carried forwardly projecting arms 33 forming part of the sighting mechanism. Further, one of the discs 40 26 also carries a circular rack 34 actuatable by a pinion 35 to produce the vertical traverse of the guns 32.

The gun sight itself is indicated at 40 as a unit and consists generally of an instrument having an objective lens producing an image upon a small rectangular screen visible to the gunner. This sight 40, in the present invention, is mounted at the forward end of a member 41 hinged at its rear end to the stationary arm 30 and having its forward end supported by two arms 42 hinged thereto and at their other ends hinged to the arms 33 fixed to discs 26. The latter are preferably fixed together at their outer ends by means of a cross member 26A. This cross member 55 26A serves to maintain the spacing of the

arms 33 and also acts as a stop or abutment for adjusting screws 45, the latter passing through a cross member 46 fixed between the arms 42.

Instead of the member 46, as shown in Figures 2 and 5, the spacer may consist of a cam 126A, as shown in Figure 12, the ends of which are supported between the arms 42. This cam 126A bears against the cross member 26A when the guns are in extreme depression. In this case, by rotating the cam, accurate equal adjustment of the pivots 33A is obtained in the slots cut in arms 33.

In assembling the sight mounting, the arms 42 are pivoted to the member 41, carrying the sight, so that the distance between the pivot point 42A and the point 40A, where member 41 is hinged to the stationary arm 30, is the same as the distance between the center 26B of discs 26 and the point 33A, where the arms 42 are pivoted or hinged to arms 33. And, while the length of arm 30 is fixed, the arms 42 are adjustable in length but approximately as long as the arm 30, from point 40A to its contact with drum 25 when considered as a tangent to the latter.

The four-sided figure thus produced, having one stationary side, changes its shape when three of its sides are moved, as they necessarily are when the discs 26 are rotated to produce the vertical traverse of the guns, and, when this change of shape is produced, the member 41 stays approximately parallel with the opposite side, namely, the line between pivot point 33A and disc center 26B. The parallelism is, however, only approximate since adjustment of the device must allow for the trajectory of the bullets.

In Figure 9, for example, the guns are indicated as sighted at a target at a selected range and at the same level, and are slightly elevated. The sight itself is of course exactly horizontal. In this figure, the axis of the gun bore is indicated by the line 32A. This setting means that the sides 42 of the quadrilateral must be shortened and such adjustment is provided for as described later. With the sides of the quadrilateral shortened, as the guns are elevated, the relative positions of the sides 33 and 41 of the quadrilateral changes and gradually approaches parallelism until the guns are aimed vertically upward when parallelism is reached. This change is indicated in Figures 9, 10 and 11, showing the guns aimed respectively, at a target at the same level, at one about 45° up, and at one directly above.

As mentioned above, the arms 42 are adjustable in length and such adjustability may be produced by the structure indicated in Figure 6. In this figure, each arm 42 is shown as having a slotted eye 42B passing through the arm and through a recess 42C in which is a spring 42D.

The stud 42A fixed in member 41 passes through the eye 42B and recess 42C and is pressed toward the upper end of the slot by the spring 42D, downward adjustment had by means of a screw 42E and lock nut 42F. The stud 42A will be provided with a suitable nut 42H and the recess covered by a suitable shield 42I.

In the modified form, as shown in Figures 14 to 16, the gun sight, indicated at 40, is the same as shown in previous figures, and is mounted on the forward end of a member 141, which in turn is fixedly mounted between the arms 130 hinged at their rear ends to the drum 25, and being supported forwardly by two arms 142 hinged thereto, and at their other ends hinged to the arms 133 fixed to discs 26. These arms 133 are fixed

together at their outer ends by a cross member 26A, as in the construction shown in Figures 1, 2 and 5.

In this embodiment of the invention, the arms 130 are hinged at the stationary pivot point 130A at the rear of drum 135. The arms 142 are hinged at one end to the arms 133 at 133A, which arms 133 are fixed to and move with the discs 26 around the center 26B. The arms 142, which are fixed in length, are hinged at their upper ends to arms 130, at the points 50A.

The pivots 50A for the arms 142 are movable in slots in the arms 130, and pass through these slots into the cross member 50 carried by the member 141 and movable forward and backward through the action of the screw 51 carried by member 141. Movement of the member 140 therefore moves the pivot pins 50A forward and backward in the slots 50B. These slots are shaped in such a way as to cause the line of sight to be parallel to the line of fire when the guns are in a vertical position at any location of the pivot 50A in the slot. However, when the line of sight is horizontal, the position of pivot 50A can be adjusted so as to give any required amount of compensation for trajectory.

The four-sided figure thus produced, having one stationary side, changes its shape when three of its sides are moved, as they necessarily are when the discs 26 are rotated to produce the vertical traverse of the guns, and, when this change of shape is produced, the member 141 stays approximately parallel with the opposite side, namely, the line between the pivot point 133A and disc center 26B. The parallelism is, however, only approximate since adjustment of the device must allow for trajectory of the bullet. This setting means that the pivot point between member 130 and arms 142 must be lowered in the slot and such adjustment is provided for as described later. Since the slot is made to always give parallelism in vertical position, the trajectory compensation will be a maximum at horizontal and approaches parallelism until the guns are aimed directly vertically upward when parallelism is reached. This change is substantially the same as that indicated in Figures 9, 10 and 11, showing the guns aimed respectively, at a target at the same level, at one about 45° up, and at one directly above.

As mentioned above, the pivot point is adjustable in the slots in member 130 and such adjustability may be produced by the structure indicated in Figure 16. A shaft 51, having a knob 55 on one end, is fixed to rotate in a hole in member 141 and a section of length on the other end is threaded. The threaded portion of member 51, acting as a lead screw, engages similar internal threads cut in cross member 50. By turning the knob on the end of shaft 51, the pivot point 50A, around which arms 142 are hinged, is moved to the desired position.

I am aware that the invention may be embodied in other specific forms without departing from the spirit or essential attributes thereof, and I therefore desire the present embodiments to be considered in all respects as illustrative and not restrictive; reference being had to the appended claims rather than to the foregoing description to indicate the scope of the invention.

I claim:

1. A sight mounting for guns arranged for vertical traverse upon a suitable support, said mounting consisting of a sight carrying member 75 above said guns, a supporting arm for said mem-

ber extending upward and rearward relative to said guns and fixed to said gun support, the sight carrying member being hinged to said arm, a supporting leg hinged at its upper end to said member and at its lower end to structure fixed to the guns and movable therewith, and means for adjusting the length of said leg whereby to vary the relative position of said sight carrier member and the axis of a gun.

2. In a machine gun mounting a drum mounted rigidly upon a suitable support and having its axis arranged horizontally, discs rotatably mounted in the ends of said drum, machine gun supporting platforms fixed to said discs crosswise thereof, an arm fixed to said drum and extending upward at an acute angle, arms fixed to said discs and extending substantially horizontally in the direction opposite that of the said fixed arm, a member hinged at one end to said fixed arm, supporting legs hinged to said member and to the

arms carried by the discs, said legs being adjustable in length, and a gun sight mounted upon said member.

3. A gun and gun sight mounting comprising a circular member mounted for rotation about a horizontal axis, a gun platform fixed to said circular member below the center thereof whereby the axis of the gun barrel may be arranged to intersect said horizontal axis, arms fixed to said circular member and extending in the direction of the gun muzzle and parallel to the gun barrel, a stationary arm extending in the opposite direction and diagonally upward, a gun sight supporting member hinged to the stationary arm and having a gun sight fixed thereto, legs hinged to said supporting member and to the first mentioned arms, and means for adjusting the length of said legs whereby to adjust the relation between said sight and the axis of the gun barrel.

MAYNARD W. TUCKER.
